CANDY TABLET

John Ray Barnes, Warson Woods, Mo., assignor to Sunline, Inc., Crestwood, Mo.

Filed Oct. 2, 1972, Ser. No. 294,456

Term of patent 14 years

Int. Cl. D1—02

U.S. Cl. D1—12

FIG. 1

FIG. 2

FIG. 3

FIG. 4

FIG. 1 is a view in plan of one side of a candy tablet embodying my new design;

FIG. 2 is an edge view of the tablet;

FIG. 3 is a view in plan of the other side of the tablet from FIG. 1; and

FIG. 4 is a section on line 4—4 of FIG. 1.

I claim:

The ornamental design for a candy tablet, substantially as shown.
